(57) **CLAIM**

The ornamental design for a dry storage bag, as shown and described.

DESCRIPTION

FIG. 1 is a front perspective view of a first embodiment of a dry storage bag;

FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is a rear perspective view thereof;
FIG. 9 is a front perspective view of a second embodiment of a dry storage bag;
FIG. 10 is a front elevation view thereof;
FIG. 11 is a rear elevation view thereof;
FIG. 12 is a left side elevation view thereof;
FIG. 13 is a right side elevation view thereof;
FIG. 14 is a top plan view thereof;
FIG. 15 is a bottom plan view thereof;
FIG. 16 is a rear perspective view thereof;
FIG. 17 is a front perspective view of the second embodiment with a gusseted bottom expanded;
FIG. 18 is a rear perspective view of the second embodiment with the gusseted bottom expanded;
FIG. 19 is a lower perspective view of the second embodiment with the gusseted bottom expanded;
FIG. 20 is a front perspective view of a third embodiment of a dry storage bag;
FIG. 21 is a front elevation view thereof;
FIG. 22 is a rear elevation view thereof;
FIG. 23 is a left side elevation view thereof;
FIG. 24 is a right side elevation view thereof;
FIG. 25 is a top plan view thereof;
FIG. 26 is a bottom plan view thereof;
FIG. 27 is a rear perspective view thereof;
FIG. 28 a front perspective view of the third embodiment with a gusseted bottom expanded;
FIG. 29 is a rear perspective view of the third embodiment with the gusseted bottom expanded; and,
FIG. 30 is a lower perspective view of the third embodiment with the gusseted bottom expanded.
The broken lines in the drawings depict portions of the dry storage bag that form no part of the claimed design.
